UNITED STATES PATENT OFFICE.

AGNES S. ADAM, OF WASHINGTON, DISTRICT OF COLUMBIA.

DOOR-CHECK.

SPECIFICATION forming part of Letters Patent No. 784,098, dated March 7, 1905.

Application filed June 17, 1904. Serial No. 212,977.

To all whom it may concern:

Be it known that I, AGNES S. ADAM, a citizen of the United States, and a resident of the city of Washington, in the District of Columbia, have invented a new and useful Improvement in Door-Checks, of which the following is a specification.

My invention relates to an improvement in door-checks, the object being to provide 10 a simple and inexpensive check for doors whose function is to directly sustain the jar or shock of a door when slammed or closed by a spring whereby to prevent noise and jar; and with the foregoing objects in view my in- 15 vention consists in a barrel or cylinder adapted to be secured to a door-jamb and having a buffer, one end of which is faced with rubber or other soft material adapted to be struck by the door and the other end with a piston 20 fitted to the wall of the barrel or cylinder and adapted to coöperate with one end of the latter to catch and compress the air between the head and the piston whereby to form an air-cushion which sustains the impact caused 25 by the door closing against the buffer and gradually exhausts between the piston and bore of the cylinder or in other convenient manner, permitting the door to entirely close, and a light spring of sufficient resiliency to 30 force the buffer outward upon removing external inward pressure therefrom.

My invention further consists in certain novel features of construction and combinations of parts which will be hereinafter de- 35 scribed, and pointed out in the claims.

In the accompanying drawings, Figure 1 is a side view of my preferred form. Fig. 2 is a longitudinal section, and Figs. 3 and 4 are plan views of modifications. 40 A represents the barrel or cylinder, and B' are the heads, the heads preferably having annular flanges 11 thereon adapted to receive the ends of the barrel or cylinder. These heads are provided with outwardly-turned 45 flanges 22, which have holes 33 therein to receive screws or similar means by which the device is secured in position. These flanges might be turned in the opposite direction, as shown in Fig. 3, or they might be directly on 50 the cylinder, as shown in Fig. 4. Any one

of the several forms will answer my purposes, and it is obvious that still other forms might be adopted.

Fitted to the bore of the barrel or cylinder is the cup-shaped piston 4, between which and the rear end or head of the barrel or cylinder the compression-chamber 5 is formed, the air suddenly caught therein adapted to form a cushion for the buffer 6, held on the outer end of piston-rod 7, in that way sus- 60 taining the shock of a door being suddenly slammed or closed, thus effectually preventing noise and jar.

Confined within the cupped-out center of the piston and the flanged head of the cylinder at the rear is a slender spiral spring 8, the tension of which is just sufficient to restore the piston and buffer to their normal outward position after the door shall have been opened preparatory to sustaining the 70 impact of the door upon being again closed. This spring is of such construction and dimensions that it does not interfere with the piston being forced in the full distance. The spring is not sufficiently strong to afford re- 75 sistance to the buffer, as the air-cushion alone does that. The sole object, purpose, and function of the spring is to force the buffer outward in position to perform its buffering function. 80

From the foregoing it will be seen that I have provided a simple device for the accomplishment of the purposes sought, and primarily it is such a device as may be manufactured and marketed at a comparatively slight 85 expense.

It is evident that slight changes might be resorted to in the form and arrangement of the several parts described in addition to those herein mentioned without departing 90 from the spirit and scope of my invention, and hence I do not wish to limit myself to the exact construction herein set forth; but,

Having fully described my invention, what I claim as new, and desire to secure by Letters 95 Patent, is—

1. As an article of manufacture, a pneumatic door-check comprising a barrel or cylinder, heads, a piston, piston-rod and buffer, the device constructed and adapted to be se- 100

cured to the door-jamb, and the rod secured to the piston and guided through one of the heads and carrying the buffer at its outer end in position to sustain the pressure of the door in closing.

2. The combination with a barrel or cylinder, heads having base-flanges thereon by which to secure them in position and annular flanges to receive the ends of the barrel or cylinder, of a cup-shaped piston fitted to the bore of the barrel or cylinder, and adapted to form an air-cushion between it and one

head of the barrel or cylinder, a piston-rod, a buffer on its outer end, and a spiral spring confined in the air-cushioning chamber for 15 restoring the buffer to its normal position.

In testimony whereof I have signed this specification in the presence of two subscribing witnesses.

AGNES S. ADAM.
